UNITED STATES PATENT OFFICE.

EMILE N. TROTTIER, OF NORTH ADAMS, MASSACHUSETTS.

GAS-STOVE VALVE-LOCKING DEVICE.

Application filed January 11, 1927. Serial No. 160,409.

This invention relates to new and useful improvements in means for attachment to the valves of gas stoves whereby the same may be securely locked in open or closed position or at any point therebetween to prevent the accidental turning of the valve, or the intentional turning of the same on the part of small children.

An important object of the invention is to provide a device of this character that is readily attachable to valves on conventional types of gas stoves without in any manner whatever altering the structure of the valve, nor of the directly associated parts of the stove, or without requiring any unusual skill.

A still further and important object is to provide a locking attachment of this character that is extremely simple of construction, inexpensive of manufacture, and one that is highly well adapted for all the purposes intended.

With the foregoing and other objects in view as the nature of the invention will be better understood, the same comprises a novel form, combination and arrangement of parts hereinafter more fully described, shown in the accompanying drawing and claimed.

In the drawing wherein like reference characters indicate corresponding parts throughout the several views:

Figure 1 is a side elevation of one of the control valves of a conventional gas stove disposed beneath the gas distributing pipe and a particular burner, said valve being equipped with my improved means for facilitating the locking of the valve.

Figure 2 is a section through the stem of the valves beneath the handle thereof for disclosing the valve body attachable unit in top plan, and

Figure 3 is a view partly in side elevation and partly in vertical cross section of said unit.

Now having particular reference to the drawing 5 designates a conventional gas stove control valve the inlet nipple of which is in communication with the gas distributing pipe 6, while the exhaust nipple is in communication with a particular burner of the stove. This type of valve includes the usual vertically projecting stem 7 upon the upper end of which is disposed a handle 8 for facilitating the proper and easy turning of the stem to move the valve to open or closed position.

In carrying out my invention I provide a two-plate clamp designated generally by the reference character 9, the same consisting of a pair of clamp plates 10 and 11 that are adapted for disposition over the upper end of the valve stem 7 as well as the headed connection between said stem and the handle 8. The four corners of these plates are provided with openings whereby the same may be rigidly secured together by set screws or the like at the four corners thereof designated 12. Furthermore, threaded within the upper edge of one of these plates or between both of said plates is a set screw 17 that may be turned downwardly into engagement with the threaded connection between the stem 7 and handle 8 to positively frictionally bind the clamp upon said connection.

One of the plates carries at its inner lower corner a lateral lug 14 formed with a vertical threaded opening through which is threaded an elongated set screw 15 the upper end of which is equipped with a thumb knob so as to facilitate the turning of the screw.

The invention further consists of a unit constructed for rigid attachment to the body of the valve 5 and this unit is designated generally by the reference character 16, detailed in Figure 3. This unit consists of a semi-circular plate 17 provided throughout substantially its entire length with spaced openings 18, the center of this plate being formed at its inner edge with a depending arm 19 that is shaped to snugly fit against the body of the valve 5 while the lower end of the arm is formed with a forwardly extending pin 20, the length of the arm being such that this pin will engage freely beneath the lower end of the stem 7 of said valve.

The unit 16 further consists of a plate 21 of relatively wide formation as indicated in Figure 1 and so shaped as to snugly engage the opposite face of the body of the valve 5, while the upper edge of this plate is formed with openings for registering with threaded openings in bosses 22-22 formed at the opposite ends of the semi-circular plate 17 and at the bottom side thereof. The lower end of the plate 21 is formed also with an opening for registry with an opening in the adjacent end of the forwardly extending pin 20 of the arm 19 so that the plate 21 may be secured to said pin and to said bosses 22 by set screws 23.

Obviously the member of the unit 16 may be rigidly connected together, and this upon either side of the valve 5 depending upon the direction of turning of the handle 8 to 5 cut on or off the flow of gas.

It will furthermore be readily understood that when it is desired to lock the control stem 7 of the valve in fully open or closed position or at any position intermediate the 10 full open or closed position, it will only be necessary to thread the elongated screw 15 downwardly so as to engage the lower end thereof within the proper opening 18 of the semi-circular plate 17.

15 In view of the foregoing description when considered in conjunction with the accompanying drawing, it will at once be apparent that I have provided a highly novel, simple, and efficient device for ready association 20 with the valves of gas stoves so as to permit said valves to be positively locked either when fully opened or closed, or at any intermediate position and that is otherwise well adapted for all the purposes heretofore 25 designated.

Even though I have herein shown and described the invention as consisting of certain detail structural elements, it is nevertheless to be understood that minor changes 30 may be made therein without affecting the spirit and scope of the appended claims.

Having thus described the invention, what I claim is:—

1. In combination with a gas stove valve, 35 wherein the latter includes a body, and a valve stem handle, a sectional clamp rigidly attached to the valve stem handle at the inner end thereof, said clamp comprising a pair of complementary opposed plates, a 40 laterally projecting lug formed on the lower side portion of one of the plates, said lug being formed with a vertical threaded bore, an elongated screw threaded rod vertically movable through the threaded bore of 45 the lug, and means associated with the body of the valve for receiving the lower end of the screw threaded rod at predetermined positions of the valve stem handle for locking the valve in such predetermined 50 position.

2. In combination with a gas stove valve,

wherein the latter includes a body, and a valve stem handle, a vertically movable locking member carried by the valve stem handle, a sectional unit detachably rigidly associated with the valve body and including a horizontally arranged semi-circular plate having spaced openings throughout the length thereof for receiving the lower end of the vertically movable locking member whereby the valve may be locked in any predetermined position, said unit further including an arm depending from the semi-circular plate for disposition against one side of the valve body, a plate member for disposition against the opposite side of the valve body, and means for detachably securing the plate member and the arm together. 55

3. In combination with a gas stove valve, 60 wherein the latter includes a body, and a valve stem handle, a vertically movable locking pin carried by the valve stem handle, a substantially semi-circular curved plate arranged horizontally beneath the valve stem handle, an arm depending from the plate for disposition against one side of the valve body, a plate like member disposed against the opposite side of the valve body, means for detachably and rigidly securing the depending arm and the complementary plate-like member together on the valve body, and the horizontally disposed semi-circular plate being provided with a series 65 of spaced openings for receiving the lower end of the vertically movable locking pin 70 for locking the valve in any predetermined position. 75

4. In combination with a gas stove valve, 80 wherein the latter includes a body, and a valve stem handle, a clamp rigidly attached to the valve stem handle, an elongated screw threaded vertically through an opening in said clamp, and a sectional unit detachably rigidly associated with the valve body and including a horizontally arranged curved plate having spaced openings throughout the length thereof for receiving the lower end of the screw whereby the valve may be maintained locked in predetermined position. 85

In testimony whereof I affix my signature.
EMILE N. TROTTIER.
